DESIGN FOR A COMBINATION ASH AND GARBAGE CABINET

John Detoro, Milwaukee, Wis.

Application August 6, 1945, Serial No. 121,268

Term of patent 14 years

(Cl. D33—19)

To all whom it may concern:

Be it known that I, John Detoro, a citizen of United States and resident of Milwaukee, in the county of Milwaukee and State of Wisconsin, have invented a new, original, and ornamental Design for a Combination Ash and Garbage Cabinet, of which the following is a specification, reference being had to the accompanying drawing, forming part thereof.

Fig. 1 is a perspective view of a combination ash and garbage cabinet, showing my new design as it appears from the front thereof; and

Fig. 2 is a perspective view as seen from the rear.

I claim:

The ornamental design for a combination ash and garbage cabinet, as shown.

JOHN DETORO.
